UNITED STATES PATENT OFFICE.

JOHN MORRISON, OF LEOMINSTER, MASSACHUSETTS.

MAKING BRUSHES.

1,265,808.

Specification of Letters Patent. Patented May 14, 1918.

Application filed April 13, 1916. Serial No. 90,966.

To all whom it may concern:

Be it known that I, JOHN MORRISON, a citizen of the United States, residing at Leominster, county of Worcester, and State 5 of Massachusetts, have invented certain new and useful Improvements in Making Brushes, of which the following is a specification.

Reference may be had to the accompanying drawings, and the reference characters marked thereon, which form a part of this specification. Similar characters refer to similar parts in the several figures therein.

This invention relates to the manufacture 15 of brushes made of a bristle-supporting pad or body of composition mounted within a cover or receptacle of thin sheet-material such as celluloid or the like.

The principal object of the invention is to 20 obtain a more intimate contact between the bristle pad or body and the receptacle or covering of sheet-material, whereby they form a substantially solid structure.

Figure 1 of the drawings is a view in vertical cross-section of a brush made in accordance with my invention.

Fig. 2 is a view in vertical cross-section of the apertured bristle-supporting die-plate used in making brushes by my improved 30 method, the plate being filled with bristles.

Fig. 3 is a similar view of the upper die-plate, up-side-down, and containing a receptacle of thin sheet-material and therewith in a mass of hot plastic composition preparatory to inverting the same upon the die-plate containing the bristles.

Fig. 4 is a vertical cross-section showing the upper die-plate and contents inverted upon the bristle-supporting die-plate, but before the die-plates have been pressed together.

Fig. 5 is a similar view showing the die-plates pressed together and the brush formed between them.

Fig. 6 is a vertical cross-section of the receptacle of sheet-material which forms the outer surface of the brush-back.

Fig. 7 is a similar view of a receptacle having its edge partly inturned preliminary 50 to the molding operation.

Referring to the drawings wherein the invention is shown in preferred form, 1 is the lower die-plate of a brush-mold having on its upper side a molding surface, 2, with numerous perforations, 3, formed therethrough

adapted to receive small knots or bunches of bristles, 4, the ends of which bristles project above said molding-surface.

The upper die-plate, 5, has its cavity of the form which is to be imparted to the finished 60 brush.

In carrying out my invention, I employ a receptacle, 5, of thin sheet-material, such as celluloid, which is adapted to cover and form a finished surface for the brush-back, except that portion thereof, from which the bristles project.

The upper die-plate, 6, is inverted, the receptacle, 5, is placed therewithin, and a quantity of hot plastic material is deposited 70 within said receptacle.

The said upper die-plate, receptacle, and hot composition are next inverted upon the bristle-supporting die-plate in the position shown in Fig. 4, and the die is then placed 75 in a press and the die-plates forced together causing the hot composition to be pressed into intimate contact with, and to fill, the receptacle, and to be forced between and around the bristle-ends and given a finished 80 surface by the molding-surface, 2.

The die is left in the press until the composition has cooled and hardened, after which the die-plates are separated and the finished brush is removed.

The sheet-celluloid becomes softened and plastic under the influence of the heat from the composition so that it readily conforms to the inner surface of the die and retains said form when cold.

The bristle-supporting die-plate is preferably formed with a groove, 7, extending around the space into which the bristles project and the sides of the receptacle, 5, are made of sufficient depth so that upon engagement with said groove, 7, they are inturned upon the bristle-supporting face of the composition pad, as shown in Figs. 1 and 5.

If desired, the edges of the receptacle 100 may be inturned before the receptacle is placed in the die, such form being shown in Fig. 7, in which case, however, the final form will be given to the inturned edge by the die under the influence of the heat from the 105 composition.

The receptacle or cover may be made of any desired thin sheet-material which becomes plastic when heated, celluloid being well adapted for the purpose.

Textile fabric impregnated with shellac may also be employed, as well as paper coated with celluloid.

In the finished product the receptacle or cover is in molded intimate contact with the composition pad, forming therewith a substantially solid structure, the composition pad supporting in form the sheet-material and the latter reinforcing the composition 10 and adding strength thereto.

Any of the usual compositions for making brushes may be employed, which become plastic when heated.

A mixture of gum and pigment is suitable 15 for the purpose.

What I claim as new and desire to secure by Letters Patent is:

1. That improvement in the art of making brushes which consists in simultaneously 20 molding into form and intimate contact under the influence of heat from the composition itself, a bristle-supporting body of composition while hot and a receptacle and cover therefor of thin sheet-material, said sheet-25 material and composition being plastic when heated.

2. That improvement in the art of making brushes which consists in inturning under 30 the influence of heat from the composition edge-portions of a receptacle of thin sheet- material over the edges of a bristle-supporting body of hot composition contained within

in said receptacle, said composition and sheet-material being plastic when heated.

3. That improvement in the art of making 35 brushes which consists in supporting bristles in an apertured die-plate with ends projecting beyond a molding-surface on the plate, applying to said ends of the bristles a hot 40 mass of plastic composition covered by a receptacle of thin sheet-material plastic under the influence of heat, and compressing 45 said heated composition and said receptacle into form and intimate contact between said die member and a co-operative die-member.

4. That improvement in the art of making 50 brushes which consists in supporting bristles in an apertured die-plate with ends projecting beyond a molding-surface on the plate, applying to said ends of the bristles a hot 55 mass of plastic composition covered by a receptacle of thin sheet-material plastic under the influence of heat, and compressing said heated composition and said receptacle into form and inturning the edge of the receptacle upon the molded face of the composition between said die-plate and a co-operative die-plate.

In testimony whereof, I have hereunto set my hand this 1st day of April, 1916.

JOHN MORRISON.

Witnesses:

JOHN MURRAY,
HARRY C. FALLON.
